DEMOUNTABLE FORM FOR POURED CONCRETE

Russell L. Geer, Grand Island, Nebr.

Application February 10, 1941, Serial No. 378,169

7 Claims. (Cl. 25—131)

The present invention relates to demountable forms for poured concrete, and has particularly to do with the problem of providing forms of such character for use in making walls of angular or corner configuration.

One general object of the invention is to provide a novel and simplified system of elements which can be easily erected, or taken down, in forming a poured concrete wall of angular configuration.

More specifically, it is an object of the invention to provide an improved, demountable corner form arrangement such that a minimum amount of change in the same is required in setting up forms for walls of a wide variety of thickness.

Another object is to provide an improved form of structure such that it can be used in forming the merging corner between either two or three wall forms, as the requirements of a particular structure may dictate.

The invention also resides in various improvements and innovations in the corner form arrangement disclosed, by virtue of which ease of erection and dismantling, simplicity of manipulation, and wide flexibility of use, are all combined in an extremely simple and rugged structure of low cost.

Further objects and advantages of the invention will become apparent as the following description proceeds, taken in connection with the accompanying drawings in which:

Figure 1 is a fragmentary perspective view of a form embodying the invention.

Fig. 2 is a detail perspective view of a cross-tie clamp included in the arrangement of Fig. 1.

Fig. 3 is an enlarged plan view of the form shown in Fig. 1.

Figs. 4 and 5 are detail perspective views of, respectively, a cross-tie bar and key included in the apparatus of Fig. 1.

Figs. 6 and 6^a are diagrammatic plan views showing, respectively, the structurally separate form parts and assembled form parts for a form constructed in accordance with the present invention.

Figs. 7 and 7^a are diagrammatic views corresponding to Figs. 6 and 6^a but showing the elements used in a form for a wall of lesser thickness than that of Fig. 6.

Figs. 8 and 8^a are diagrammatic views also corresponding to Figs. 6 and 6^a showing the form elements arranged for a T-shaped corner junction.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications

and alternative constructions falling within the spirit and scope of the invention as expressed in the appended claims.

In the exemplary construction (see Figs. 1 and 3) I have shown the invention as embodied in a demountable form assembly for a poured concrete wall, comprising, in brief, a corner form A and a pair of wall forms B and C which are joined by the corner form, only the end portions 10 of the wall forms adjacent the corner form being shown. The wall forms B and C are demountable and each comprises inner and outer wooden mold walls or mold boards 10 and 11 secured together by a system of removable cross tying more particularly described and claimed in my copending application S. N. 345,296, filed July 13, 1940. Herein I have described only so much of the wall form arrangement as coacts directly with the elements of the corner form A.

20 The corner form A comprises inner and outer form elements, designated generally as 12 and 13, respectively, which define between them a wall cavity of right angular or L-shape to receive the poured concrete. The forms 12 and 13 include mold walls of angular configuration which constitute, in effect, continuations of, or merge with, the mold walls 10 and 11 of the wall forms B and C, but from which they are structurally separable.

25 Turning now to the details of the outer corner form 13, it includes two right angularly disposed mold wall or mold board sections made up of an outer layer of rough lumber 14 covered by an inner facing 15 of smooth sheet material such as plywood. A cove 16 (Fig. 3) presenting an arcuate inner face extends along the juncture between these two mold wall sections.

On the exterior of the mold wall sections for the outer corner form 13 is a reinforcing arrangement including a vertically extending angle iron 17 which embraces the corner juncture of the mold wall sections as well as the cove 16 and rigidly reinforces the same, being bolted to the mold wall sections. Welded to the angle iron 17 at spaced points along the latter's length are a plurality of vertically spaced L-shaped metal reinforcing members 18 (only one of which is here shown). These members 18 are fashioned from flat metal stock and extend generally horizontally along respective mold wall sections in reinforcing relationship thereto. Wooden plates or timbers 19 are screwed to the lower face of each of the L-shaped reinforcements 18 and the mold walls may be nailed or otherwise secured to the inner edges of these wooden plates. In this manner an extremely rigid and durable outer corner form is provided.

The inner corner form 12 includes as one of its principal elements an upright corner post herein shown as being a relatively heavy timber 20 of

square cross section. Its outer corner is beveled (see Fig. 3) to form clearance for the herein-after described clamps which it abuts. The two adjacent inner faces of this corner post are faced by mold boards or walls 21, nailed to the corner post and suitably rounded as indicated at 22.

To form a firm, tight joint between the mold walls of the wall forms and the corner form members, strips of hardwood 23 may be secured to the edges of the wall form mold boards and strips 24 to the edges of the mold walls on the outer corner form 13 (Fig. 3). These hardwood strips and the edges of the mold boards 21 are fashioned to form tongue and groove joints as indicated. This not only affords a tight joint but also assures proper alignment of the mating portions of the mold walls.

Provision is made for removably securing both the outer and inner corner forms 13 and 12, respectively, to vertical reenforcing studs 25 and 26 of the wall forms B and C. It will be observed in Figs. 1 and 3 that the studs 25 are fixed to the outer side of the outer mold walls of the wall forms and are disposed adjacent the ends thereof. Similarly, the studs 26 extend in reenforcing relation along the outside of the inner mold walls of the wall forms adjacent the ends of the latter. To secure the outer corner form 13 to the studs 25, bolts 27 are passed through registering holes in the studs 25 and through complementally located vertical reenforcing studs 28 fixed to the exterior of the outer corner form. The studs 28 are held in place by bolts 29 passing through apertured, angular flanges 30 on the ends of the L-shaped members 18.

The studs 26 on the inner sides of the wall forms are similarly secured by through fasteners to an adjacent vertical reenforcement of the inner corner form 12. In the illustrative construction bolts 31 are disposed substantially at right angles to each other (Fig. 3) and pass through the corner post 20, projecting from the respective outer faces of the latter. These through bolts 31 are each threaded in a pair of nuts 32 welded together and countersunk in the respective inner faces of the corner post. It will be noted that the mold boards 21 cover these countersunk nuts.

The drawing together of the complementally located uprights of the corner and wall forms, by the through bolts 27 and 31, may also serve to cause these uprights to grip and hold in position clamps or brackets 33 which are included in the cross tying arrangement for the wall forms. In the present instance the clamps 33 have been shown as being of a novel form described and claimed in my copending application S. N. 345,296 referred to above. Upon reference to Fig. 2 it will be seen that each of the brackets 33 is fashioned as a unitary structure from a single metal plate having a body portion 34 which is generally square in outline. From two adjacent edges of this body 34 integral ears 35 and 36 are bent to overlie in spaced relation the opposite faces of the body 34. The ears 35, 36 thus define with the body a pair of right angularly related channels on opposite sides of the body 34 and to receive one of the wall form studs 25 or 26, to which it is applied.

Tapering tie rods 37 (see Figs. 3 and 4) are arranged to traverse the wall form and are suitably secured to opposed pairs of brackets 33. For this purpose, the end portions of the tie rods are received between and guided by opposed pairs of lugs 38 struck out from the ear portions of

each of the brackets. Furthermore, slots 39 are formed in each of the brackets adjacent the guiding lugs 38. In each of the tie rods 37 a corresponding slot 40 is formed adjacent one end of the rod and a series of such slots 41 at spaced points adjacent the other end. Keys 42 (see Figs. 3 and 5) are inserted through registering ones of the slots in the brackets and tie rods to hold them against displacement with respect to each other. In the assembly of these brackets in the illustrated structure, engagement of a bracket channel with any stud 25, 26 will, as shown in Fig. 3, dispose an ear thereof between that stud and the complementary member 20 or 28. When the associate through bolts 27 or 31 are tightened, the brackets will be secured in place.

The versatility of the sectionalized system of forms described can best be appreciated upon reference to Figs. 6 to 8^a. The transverse ties have been omitted from these figures for clarity. In Fig. 6, I have shown diagrammatically the parts of a corner form A and wall forms B and C prior to their assembly in the configuration indicated in Fig. 6^a. It should be noted that the ends of the inner and outer corner forms are substantially aligned with each other in a direction transverse of the wall cavity which they define between them. This being the case they are, when assembled, properly aligned with respect to the complementary ends of the wall forms which are in similar alignment with each other. It is obviously a simple matter to bolt the corner form elements 12 and 13 to the wall forms to effect a strong rigid structure, and equally simple to unbolt them and disassemble the form for use at another point and without injuring the form parts.

In order to set up a form for a wall of somewhat lesser thickness, such as that indicated in Fig. 7^a and still maintain the transverse alignment of the ends of the wall forms, it is necessary merely to use a set of form elements like that indicated in Fig. 7 which is identical with those of Fig. 6, except that the inner corner form 12^a comprises a corner post 20^a of proportionately larger dimensions and which is also faced by mold boards of proportionately greater width. Hence, the form elements herein disclosed can be used in the erection of an L-shaped corner form of any desired thickness of wall, within a wide range of wall thicknesses, merely by substituting an inner corner form of proportionate size. The same outer corner form 13 is used and, of course, the same wall forms B and C can be used, both irrespective of wall thickness.

A still further variation of use is indicated in Figs. 8 and 8^a. In this instance the form elements are used to define a generally T-shaped wall cavity such as is used at the juncture of three wall forms B, C and D. In this case two inner corner forms 12 are utilized together with a filler wall 43, which may be simply a plain section joining the adjacent and aligned outer mold walls for two of the wall forms.

From the foregoing it will be appreciated that I have provided a wall form arrangement of extreme simplicity. Its heavy reenforcement insures great ruggedness and strength, though its general simplicity makes it low in cost as well as simple for even the unskilled to use. Because of the variety of shapes and sizes of walls which can be accommodated, maximum use is made of the demountability of the structure. Thus, the invention provides a wall form structure which may be easily and economically assembled and disas-

sembled on many successive work sites because the versatility or flexibility of shapes in which the parts can be erected makes it suitable for the variations that may be encountered in each new job.

I claim as my invention:

1. A form for poured concrete comprising, in combination, a pair of demountable wall forms disposed at an angle to each other, each of said wall forms comprising a pair of opposed mold walls defining a wall cavity therebetween for poured concrete, said mold walls having vertical reenforcing members fixed to their outer sides adjacent their respective ends, cross-ties joining the opposed mold walls of said wall forms, means including brackets having portions lying on the end edges of said reenforcing members for removably securing said cross-ties in place, inner and outer corner forms including mold walls of matching configuration disposed to join respectively the inner and outer walls of said wall forms, the outer ends of said corner form mold walls being substantially in alinement with each other in a direction transverse of the respective arms of the cavity defined therebetween, each of said corner forms having vertical reenforcing members fixed to the outer faces of their respective mold walls and extending adjacent the outer ends thereof, and means for removably securing said vertical reenforcing members on said corner forms to the adjacent reenforcing members on said wall forms and drawing them toward the latter to clamp said portions of said brackets between the adjacent reenforcing members on the wall and corner forms.

2. A form for poured concrete comprising, in combination, a pair of demountable wall forms disposed at an angle to each other, each of said wall forms comprising a pair of opposed mold walls defining a wall cavity therebetween for poured concrete, said mold walls having vertical reenforcing members fixed to their outer sides adjacent their respective ends, inner and outer corner forms including mold walls of matching configuration disposed to join respectively the inner and outer walls of said wall forms, said mold walls of the corner form being disposed in abutting edge-to-edge relation with said mold walls of the wall forms and having tongue and groove connections therewith along the abutting edges thereof, the outer ends of said corner form mold walls being substantially in alinement with each other in a direction transverse of the respective arms of the cavity defined therebetween, each of said corner forms having vertical reenforcing members fixed to the outer faces of their respective mold walls and extending adjacent the outer ends thereof, and through fasteners for drawing said vertical reenforcing members on said corner forms against the adjacent reenforcing members on said wall forms and at the same time seating the coacting elements of said tongue and groove connections.

3. In a demountable corner form for a poured concrete wall, the combination of a mold wall presenting two angularly disposed sections having a vertical line of juncture, a vertically extending angle iron fixed to the outer side of said mold wall and extending along the line of juncture between said angularly disposed sections, and a plurality of generally L-shaped reenforcing members rigidly fixed to said angle iron at spaced points along the latter's length, said reenforcing members being disposed substantially in horizontal planes with their arms embracing

the mold wall sections extending in reenforcing relation along the outer surfaces of said mold wall sections.

4. In a demountable corner form for a poured concrete wall, the combination of a mold wall presenting two angularly disposed sections having a vertical line of juncture, a vertically extending angle iron fixed to the outer side of said mold wall and extending along the line of juncture between said angularly disposed sections, a plurality of generally L-shaped metal reenforcing members rigidly fixed to said angle iron at spaced points along the latter's length, said reenforcing members being disposed generally horizontally with their arms embracing the mold wall sections and extending in reenforcing relation along the outer faces of said mold wall sections, and wooden plates extending along the arms of said L-shaped reenforcing members and fixed thereto as well as to said mold walls.

5. In a demountable corner form for a poured concrete wall, the combination of a mold wall presenting two angularly disposed sections having a vertical line of juncture, a vertically extending angle iron fixed to the outer side of said mold wall and extending along the line of juncture between said angularly disposed sections, and a plurality of generally L-shaped metal reenforcing members rigidly fixed to said angle iron at spaced points along the latter's length, said reenforcing members being disposed substantially horizontally with their arms extending in reenforcing relation along the outer surfaces of said mold wall sections, and said L-shaped members having integral means on the outer ends thereof for attachment of the same to adjacent wall forms.

6. In a form for poured concrete, the combination with a demountable wall form adapted to define one side of a wall cavity near a corner thereof, vertical reenforcing means fixed on the outer side of said wall form adjacent the end thereof nearest the corner, a cross tie supporting bracket having a portion lying on the end edge of said reenforcing means, a corner form mold wall disposed to join said wall form, vertical reenforcing means fixed to the outer face of said corner form mold wall and having a surface for abutment with the reenforcing means on said wall form, and means for drawing and securing the reenforcing means on the corner form mold wall and on the wall form together with said portion of said cross tie bracket lying between adjacent surfaces of said reenforcing means.

7. In a form for poured concrete, the combination with a demountable wall form adapted to define one side of a wall cavity near a corner thereof, vertical reenforcing means fixed on the outer side of said wall form adjacent the end thereof nearest the corner, a corner form mold wall arranged for edgewise abutment with said wall form, the meeting edges of said wall form and said corner form mold wall having a complementary tongue and groove connection, reenforcing means fixed to the outer face of said corner form mold wall and presenting a surface opposed to a surface on the reenforcing means on said wall form, and through fasteners providing connections between said reenforcing means operable to draw them securely together and at the same time seat the complementary elements of said tongue and groove connections.
